UNITED STATES PATENT OFFICE.

CHARLES C. LAMB, OF CHICAGO, ILLINOIS, ASSIGNOR OF ONE-HALF TO WILLARD M. McEWEN, OF CHICAGO, ILLINOIS.

DRIVING MECHANISM FOR WASHING MACHINES.

1,423,531.

Specification of Letters Patent. Patented July 25, 1922.

Application filed November 19, 1919. Serial No. 339,170.

To all whom it may concern:

Be it known that I, CHARLES C. LAMB, a citizen of the United States, residing at Chicago, in the county of Cook and State of Illinois, have invented new and useful Improvements in Driving Mechanisms for Washing Machines, of which the following is a specification.

This invention relates to washing machines of the type particularly adapted for domestic use, and consists in the matters hereinafter described and more particularly pointed out in the appended claims.

In the accompanying drawings—

Fig. 1 is a side view of a washing machine constructed in accordance with my invention;

Fig. 2 is a horizontal sectional view taken on line 2—2 of Fig. 1;

Fig. 3 is a vertical sectional view taken on line 3—3 of Fig. 2;

Fig. 4 is a side view of the spooled gear wheels and interposed grooved pulley for turning the basket about a vertical axis;

Fig. 5 is a perspective view of the chain for turning the basket; and

Fig. 6 is a diagrammatic view of the chain and spooled gear in mesh therewith.

The washing machine of my invention has a supporting base or stand 1 preferably in the form of a table, having four legs 2 secured to the corners of an open top frame 3. Mounted above the stand 1 are two containers 4, 5, one within the other and preferably circular in shape and with flat bottom walls.

The container 4 constitutes the outer tub of the machine and is held stationary and made larger than the inner container 5, which is mounted to turn on a vertical axis. There is a space between the walls of said containers, and the wall of the inner one is perforated so that the inner container constitutes a basket and may be used as a centrifugal wringer when rotated in one direction and at a rapid speed. The tops of the containers are open to permit the garments to be washed to be inserted in the basket 5, the cover 6 of the tub 5 being off at that time.

For washing clothes the basket is oscillated back and forth on a vertical axis, by means constructed as follows: The frame 3 is provided with a cross-bar 7, to the under side of which is secured a substantially U-shaped bracket 8 arranged centrally of the

cross-bar. Secured to the center of the bottom wall of the outer tub 4 is a journal box 9, which seats on the cross-bar 7 above the bracket 8 for supporting the tub on the stand 1. Said box 9 is removably connected with the cross-bar 7 by bolts 10 having clamp nuts 11 to permit the tub 4 to be removed from the stand when desired. To the center of the bottom wall of the basket 5 is secured a depending shaft 12, which extends downward through the bottom wall of the tub 5 and the box 9 as well as through the cross-bar 7, as shown in Fig. 3. The lower end 13 of the shaft 12 is reduced and made square to enter a complementary shaped bore in a sleeve 14 located in the bracket 8. Said sleeve 14 is provided with upper and lower gear wheels 15, 16 and an interposed grooved pulley or sheave 17, all made rigid with the sleeve, that is, they are spooled together to rotate in unison and at the same speed. Resting on the bracket 8 is a bearing plate 18 supporting bearing balls 19 for the gear member and provided with an upright stud 20 extending into the bore of the gear member. By lifting the basket 5 upward, it may be removed from the stand 1 and the outer tub 4, the shaft 12 being withdrawn from the gear member 14 and the box 9. The stud 20 holds the gear member in place to receive the squared end of the shaft 12 when the basket 5 is replaced. By the construction described, the tub 4 and basket 5 may be taken off of the stand 1 and the latter used as a table, if desired.

Secured between the legs 2 below the frame 3 is a flat plate or shelf 21, upon which is supported an electric motor 22 arranged with its armature shaft 23 horizontal. Loosely mounted on said shaft is a sleeve 24 journaled in upright standards 25 secured to the shelf 21. The portion of the sleeve between said standards is provided with a worm 26 in mesh with a worm wheel 27 above the same and mounted on a horizontal shaft 28 at the upper ends of upright standards 29 secured to said shelf 21. One end of the sleeve 24 is provided with a fixed clutch member 30 to be engaged by a clutch member 31 splined on the armature shaft 23. The clutch member 31 may be shifted into and out of clutch with the other member 30 by a yoke 32 forming part of the manually operable lever 33 fulcrumed at 34 on the

frame 3, as shown in Figs. 1 and 2. The shiftable clutch member 31 is provided with a beveled gear 35 to be moved into and out of mesh with a beveled gear 36 at the lower end of a shaft 37. The latter is supported and journaled at its lower end in a standard 38 secured to the shelf 21 and at its upper end in a bracket 39 secured to the frame 3 and extending inward therefrom, as shown in Fig. 2. At the upper end of said shaft 37 is a grooved pulley 40 in the horizontal plane of the pulley 17 and connected therewith by a belt or cable 41, as shown in said Fig. 2. To the short shaft 28 is secured a sprocket wheel 42 (Fig. 3), over which is trained a sprocket chain 43. The latter is trained over a sprocket wheel 44 on a shaft 45, horizontally arranged and supported in brackets 46 on the frame 3. At the opposite side 20 of the frame is a like shaft 45, parallel to the opposite shaft and supported in like brackets 46. Splined on each shaft 45 is a sprocket wheel 47. Said sprocket wheels 47 are in alignment and are engaged by 25 a sprocket chain 48 having, along one side thereof, rack teeth or spaced projections 49, as shown in Figs. 2 and 5. These are designed to mesh alternately with the teeth on the upper and lower gear wheels 15 and 16. The teeth 49 do not extend completely 30 around the chain, but stop at such a point that after the last tooth has left the upper gear wheel 15, the first tooth is then on the lower lap of the chain and has become 35 meshed with the teeth on the lower gear wheel 16. Fig. 6 is a diagrammatic view of the chain 48 and spooled gear 14 and shows that the teeth 49 extend only part way around the chain to accomplish the 40 object just stated. Thus, the basket 5 is oscillated about a vertical axis, first in one direction and then in the opposite direction as the chain 48 is operated by the motor 22. By such construction, the operating parts 45 are rotated continuously in one direction and an oscillation imparted to the basket 5. This is due to the fact that the teeth on the chain 48 alternately engage the upper and lower gear wheels 15, 16 and do not engage 50 said gear wheels both at the same time. Manifestly, when the teeth engage the upper gear wheel, the basket 5 is turned in one direction, and then when the teeth leave the upper gear wheel and engage the lower 55 one, the rotation of the basket is reversed, without being required to manipulate manually or otherwise any clutch parts to effect this. By oscillating the basket 5, the agitation of the water and garments is sufficient to wash the latter.

When ready for wringing, the clothes are left in the basket 5, and the water drained off from the tub through a cock (not shown). The chain 48 is then thrown out of the 65 mesh with the gear wheels 15, 16, so that

the basket 5 may be rotated rapidly and in one direction by the motor 22. To do this, I provide the sprocket wheels 47 with grooved hubs 51 engaged by yokes 52 on a shift bar 53. Said bar is moved in one 70 direction by springs 54, and in the opposite direction by a cam plate 55 at the inner end of the hand lever 33 and operating against a stud or pin 56 attached to the bar 53, as shown in Fig. 2. When the main 75 lever 33 is moved to throw out the chain 48, the clutch member 31 is released from the worm 26 to cut off power to the gear wheels 15, 16. The clutch member 31 is, however, shifted to mesh with the beveled 80 gears 35 and 36, so that the motor will rotate the basket 5 in one direction for wringing and rinsing purposes.

Any suitable means may be provided for holding the lever 33 from being moved accidentally out of any of its operative positions. Such means may be in the form of a lug on the lever and a number of sockets or recesses on the part of the stand 1 over which the lever is moved. When the lever is in its lowest 90 position, the motor oscillates the basket 5. When the lever has been moved to its uppermost position, the machine is used for wringing purposes. When the lever is in its intermediate position, both of the washing and 95 wringing mechanisms are inoperative. At this time, the clutch member 31 is out of engagement with the worm 26 and the beveled gear wheel 36.

The machine constructed as described and 100 shown is portable, compact, and easily operated. Only one lever is required to change from washer to wringer. The tub 4 and basket 5 may both be readily and easily removed for cleansing or for such other purposes as desired. The centrifugal wringer is an advantage, as the garments need not be removed from the tub for wringing purposes, and, further, the wringing may be operated until the clothes are substantially 110 dry and all water removed therefrom. Other end further advantages will be apparent to those skilled in the art to which my invention applies.

While I have shown and described in detail 115 a washing machine embodying the features of my invention, it is to be of course understood that the details of construction and arrangement of parts shown and described may be variously changed and modified without departing from the spirit and scope of my invention.

I claim as my invention:

1. In a gearing of the character described, the combination of a support, an upright 125 operating shaft rotatably mounted in said support, two toothed wheels and a pulley fixed to said shaft, an endless chain having teeth part way around the same for alternately engaging said wheels for oscillating 130

said shaft, a motor on said support for driving said chain and pulley in one direction, and a clutch mechanism for connecting either the chain or the pulley with said motor.

2. In a gearing of the character described, the combination of a support having a cross-bar, an upright operating shaft rotatably mounted in said cross-bar, a bracket secured 10 to said cross-bar, a sleeve rotatably mounted between said bracket and cross-bar and receiving the lower end of said shaft, two toothed wheels and a pulley fixed on said sleeve, an endless chain provided with rack teeth part way around the same for alternately engaging said wheels, a motor on said support for driving said chain and said pulley in one direction, and a clutch mechanism for connecting either said pulley or 15 said chain with said motor.

3. In a gearing of the character described, the combination of a support, an upright operating shaft rotatably mounted on said support, two toothed wheels and a pulley 20 fixed on said shaft, two parallel shafts journaled on said support, a sprocket wheel splined on each of said shafts, a sprocket chain engaging said sprocket wheels and having rack teeth part way around one side 25 thereof for alternately engaging said toothed wheels, a motor on said support for driving said chain and said pulley in one direction, a clutch member mounted on the armature 30 shaft of said motor, means for connecting either the chain or pulley thereto, a shift bar connected with said sprocket wheels for moving the chain out of engagement with 35 said toothed wheels, and a single operating

lever pivoted on said support for shifting said clutch member and said shift bar. 40

4. In a gearing of the character described, the combination of a support, an upright operating shaft rotatably mounted in said support, two toothed wheels and a pulley 45 fixed to said shaft, two parallel shafts journaled on said support, a sprocket wheel splined on each of said shafts, an endless chain engaged with said sprocket wheels and having rack teeth part way around on one side thereof for alternately engaging 50 said toothed wheels for oscillating said operating shaft, a motor on said support, a worm wheel on said support, a worm on the armature shaft of said motor and meshing with said worm wheel, a sprocket chain 55 connecting said worm wheel with one of said parallel shafts, a beveled gear having power transmitting connection with said pulley, a clutch member splined on said armature shaft between said beveled gear and 60 said worm and adapted to be shifted into engagement with either, a shift bar connected with said sprocket wheels for moving the chain out of engagement with said toothed wheels, a single manually operable 65 lever pivoted on the support and having one end connected with said clutch member, and coacting means between said lever and said shift bar for moving the latter when the lever is moved for connecting the pulley 70 with said motor.

In testimony that I claim the foregoing as my invention, I affix my signature, this 15th day of November, A. D. 1919.

CHARLES C. LAMB.
